US00D591711S

(12) **United States Design Patent**
Bai et al.

(10) **Patent No.:** US D591,711 S
(45) **Date of Patent:** ** May 5, 2009

(54) **MOBILE PHONE**

(75) Inventors: **Sung-Kyun Bai**, Seoul (KR);
Seog-Guen Kim, Seoul (KR);
Woo-Seung Han, Seoul (KR); **Tae-Ho Kim**, Yongin-si (KR); **Yun-Su Kim**, Seoul (KR)

(73) Assignee: **Samsung Electronics Co., Ltd.**, Suwon-Si (KR)

(**) Term: **14 Years**

(21) Appl. No.: **29/318,382**

(22) Filed: **May 19, 2008**

(30) **Foreign Application Priority Data**

Dec. 28, 2007 (KR) 30-2007-0054147
